UNITED STATES PATENT OFFICE.

ERNEST S. ROE, OF PLYMOUTH, MICHIGAN, ASSIGNOR TO MARKHAM AIR RIFLE COMPANY, OF DETROIT, MICHIGAN, A CORPORATION OF MICHIGAN.

AIR GUN.

Application filed December 21, 1925. Serial No. 76,811.

This invention relates generally to air guns and rifles of the break-down type and consists of certain novel features of construction, combinations and arrangements of 5 parts as will be more fully described and particularly pointed out in the appended claims.

In the accompanying drawings:

Figure 1 is a side elevation of a gun embodying my invention.

Figure 2 is an enlarged fragmentary vertical longitudinal sectional view through the gun.

Figure 3 is a view similar to Figure 2 but 15 showing the stock in open position.

Figure 4 is a fragmentary top plan view with parts broken away.

Referring now to the drawing, 1 is the barrel, 2 is the stock and 3 is the intermediate casing of a gun embodying my invention. As shown, the casing 3 is rigidly secured to the stock 2 and is pivotally connected to a substantially channel-shaped housing 4 rigidly secured to the barrel 1. 20 To facilitate assembly of these parts, the barrel 1 is slotted to receive the housing 4, while the side walls of the latter are preferably slotted to receive the lower wall of the barrel, thus only one bolt 5 is required 25 to secure the housing 4 to the barrel 1.

Pivotaly mounted in the housing 4, preferably adjacent to the bolt 5 is a trigger 6 having the vertically shaped forwardly extending projections 7 and 8, while slidably 30 mounted in the barrel 1 is the usual disc plunger 9 that is normally held in projected position by means of a coil spring 10. Extending through the convolutions of the spring 10 is a rod 11 that is rigidly secured 35 at its forward end to the disc plunger 9 that is provided at its rear end with a depending hook 12 which is adapted to travel in and be guided by the channel-shaped housing 4.

For drawing the plunger 9 rearwardly against the tension of the spring 10 to cock the gun, I have provided a pair of links 13 that are terminally connected to the stock casing 3 and to a transversely extending pin 15. As shown, a bolt 14 extends transversely of the casing 3 and engages aligned circular openings in the rear ends of the links 13, while the pin 15 rests on the upper edges 16 of the trigger housing 4 and en-

gages elongated slots 17 in the forward ends of the links 13.

Heretofore a suitable abutment has been provided at the forward end of the barrel to take the thrust of the spring projected plunger when released by the trigger, however such abutments are expensive to manufacture in guns of this type. When such abutments are dispensed with, the strains due to thrust are imparted by the links to the bolt 14. As a result these bolts bend 60 into arcuate form and sometimes rip or tear the walls of the casing 3. To take care of the bending action relatively long bolts have to be used. It is apparent therefore that such a construction is also very objectionable.

With the present invention I have overcome the objectionable features just referred to by providing the side walls of the trigger housing 4 with upstanding projections 19 which will take the thrust of the cross pin 15 imparted by the hook 12 when the latter is released by the trigger. Inasmuch as the distance between the bolt 14 and the projections 19 is less than the distance 75 between the bolt 14 and forward ends of the slot 17 in the links, it is apparent that the projections 19 of the housing 4 will receive the shocks and strains when the hook 12 abuts the cross pin 15 after being released 80 by the trigger and will thereby relieve the links 13 and bolt 14 of such thrust and strains. Hence shorter bolts 14 may be used and damage to the casing 3 is obviated entirely. Moreover the construction is such 90 that the cross pin 15 may be relatively short and may be readily removed and replaced whenever desired. The side walls of the barrel will prevent any accidental displacement of the pin 15 when the parts are assembled. It will also be apparent that the upper edges 16 of the housing 4 serve as guides for the pin 15 while the projections 19 serve as abutments for both the cross pins 15 and coil spring 10. Thus from the foregoing description, it will be apparent that I have provided a strong and durable gun 95 that is simple in construction and can be manufactured at a comparatively low cost.

While it is believed that from the foregoing description, the nature and advantage of my invention will be readily apparent, I desire to have it understood that I do 100 105

not limit myself to what is herein shown and described and that such changes may be resorted to when desired as fall within the scope of what is claimed.

5. What I claim as my invention is:

1. In an air gun, the combination with a spring projected hook, and trigger controlled means for detachably holding said hook, of means for moving said hook against the tension of the spring into engagement with said trigger controlled means including a cross pin engageable with the hook, and a link for actuating the pin, and means for relieving said link of strains and thrust when said hook is released by said trigger control means including a separate abutment adapted to be engaged by the pin.

10 2. In an air gun, the combination with a spring projected hook, of a guide for the hook having an abutment, and means for actuating the hook against the tension of the spring including a pin engageable with the hook and abutment, and a link having a slotted engagement with the pin.

15 3. In an air gun, the combination with a spring projected hook, of means for actuating the hook against the tension of the spring including a pin engaging the hook, and a link having an elongated slot at one end thereof engageable by said pin.

20 4. In an air gun, the combination with a spring projected hook, of a pin for actuating the hook against the tension of the

spring, and a guide for the hook having an abutment for the pin and means for guiding the pin to and from said abutment.

25 5. In an air gun, the combination with a plunger, a spring for projecting said plunger, means for actuating the plunger against the tension of said spring including a rod connected to the plunger having a hook portion, a pin engageable with the hook portion, and a link engageable with the pin, and a guide for the hook having a projection constituting abutments for both the pin and spring.

30 6. In an air gun, the combination with a spring projected hook, of means for actuating the hook against the tension of the spring including a pin engageable with the hook, and a guide for the hook having an abutment for the pin.

35 7. In an air gun, the combination with a spring projected hook, of means for actuating the hook against the tension of the spring including a pin engaging the hook, a guide for said hook having a projection constituting an abutment for said pin, and a pair of links having a slotted connection with said pin permitting the latter to engage said abutment when the hook reaches the end of its spring projected movement without imparting any thrust or strains to the links.

In testimony whereof I affix my signature.

ERNEST S. ROE.
